L. Conrad Hinde
his ATTORNEY

UNITED STATES PATENT OFFICE.

ALEXANDER KONOFF, OF NEW YORK, N. Y., ASSIGNOR TO VOICES INCORPORATED, OF WILMINGTON, DELAWARE, A CORPORATION OF DELAWARE.

VOICE DEVICE.

Application filed May 10, 1923. Serial No. 637,983.

This invention relates to a voice device for dolls and other toys and is in the nature of an improvement over the structure shown and described in my pending application Serial 5 #570,209, filed June 22, 1922.

An object of the present improvement is to reduce the required size of the device so that less space, for instance within the body of a doll, will be required to accommodate it. 10 A further object is to simplify and cheapen the structure and at the same time improve its quality of operation.

A further and more detailed object is to produce a device of the class described comprising a weight controlled bellows, to provide a sound producing element carried by the weight, to provide a post along which the weight is adapted to slide for collapsing and distending the bellows and for thereby operating the sound producing element for producing predetermined sounds, and to provide a sound box formed as a part of the weight and comprising as one of its walls a separately formed part serving also as means 20 to retain the weight connected with the bellows.

Other objects and aims of the invention, more or less specific than those referred to above, will be in part obvious and in part 30 pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention 40 :—

Figure 1 is a central vertical sectional view through a device constructed in accordance with this invention.

Figure 2, is a transverse sectional view 45 taken substantially upon the plane of II—II of Fig. 1, a part of the weight structure being broken away for disclosing the arrangement of the sound box, and

Figure 3, is a detail sectional view through 50 the weight, the section being taken upon the plane of III—III of Fig. 2.

Referring to the drawings for describing in detail the structure therein illustrated the reference character L indicates the post, 55 while the reference character G indicates

the weight element which is freely slideable along the post.

These parts are contained within a casing consisting of a tubular cylindrical shell 1 with opposite end heads 2 and 3 at the upper 60 and lower ends respectively. The post extends axially through the shell and is supported in fixed position by engagement with the heads 2 and 3, said heads being preferably formed with seats as 4 therein into 65 which the end portions of the post engage.

The post is hollow, being made usually of thin metallic tubing, and portions as 6 of the heads 2 and 3 serve to close the opposite ends of the post.

The heads are preferably of sheet metal and may be connected with the shell in any suitable manner, as for instance by having flanges 7 fitting tightly over the end portions of the shell.

The upper head 2 is perforated as indicated at 8 for the free passage of sound waves etc.

The bottom head 3 is imperforate.

The weight G is disk shaped and has a central aperture 9 for receiving the post, the diameter of the aperture being of just the proper size to permit free movement of the weight along the post. At its under surface it is provided with a cavity 10 into which is arranged a sound producing element 11, the sound producing element being held in a position parallel with the main body of the weight, that is, so that the sound producing element extends longitudinally in a direction 90 transverse to the length of the post, and concerning this it may be here remarked, that the sound producing element is necessarily of considerably greater length than thickness, in fact that its length is greater than the 95 overall thickness of the weight G. Hence arrangement of the sound producing element in the horizontal position illustrated effects a material saving in the necessary thickness of the weight.

The sound producing element is preferably held in position within the cavity 10 by being received in a non-resonant carrier 12, of cork, rubber, or the like, which is in turn held within the cavity by frictional engagement 105 with the walls of the cavity. One end as 13 of the cavity is in communication with the bellows as will be presently apparent, and the structure is such that all air passing outwardly from the bellows must pass through 110

the sound producing element and into the chamber 14 provided at the opposite end of the cavity, thence upwardly through an opening 15 formed through the material of the 5 weight and into the sound box 16 whence it travels through openings as 17 in the post and to the outside atmosphere. The passage of the air through the sounding device will cause the reed portion as 18 thereof to vibrate and thereby produce a predetermined sound and this sound will be dependent in quality and volume upon the freedom with which the air passes, hence upon the size, proportions and arrangement of the openings 17.

15 In the instance illustrated the sounds produced are intended to simulate the word ma-ma, the first syllable being sounded as the weight passes the upper openings 17 and the second syllable being produced as the weight 20 passes the lower openings 17, of the post.

The bellows as H consists of a tube of cloth or other soft material the lower annular edge of which is fixed to the casing, as for instance by being interengaged between the shell 1 25 and flange 7, and the upper annular edge of which is fixed to the weight as for instance by being fitted about the annular surface portion of the weight and being held clamped thereto by a retaining ring 19.

30 The clamp ring 19 consists of the flange portion of an inverted saucer shaped member 20 which rests upon the upper surface of the weight and constitutes in effect a part thereof, the bottom wall portion as 21 of the saucer 35 being disposed to cooperate with raised rib portions 22 of the weight so as to close, or rather provide the upper wall portion of, the sound box 16. It will be noted that the rib 6 is relatively narrow, or in other words, 40 projects from the face of the weight G for only a short distance, the primary consideration residing in the fact that this chamber is comparatively shallow and while affording an ample space for the expansion of the sound 45 waves, does not materially increase the thickness of the weight so that the said weight may have the desired length of stroke or sliding movement along the post L and at the same time can be housed within an outer casing of 50 relatively short length.

Preferably the main or body portion of the weight is formed with an annular groove 23 at its periphery for receiving the flange 19 and the material of the bellows.

55 Preferably also this recess is made to provide a ledge or shoulder portion 24 and the flange 19 is made to provide an outstanding rib 25 so that by inserting the blade of a knife or other instrument between said ledge 60 and rib the member 20 may be readily disassembled from the body of the weight upon occasion.

The rib 22 for defining the sound box 16 extends around the openings 15 and 9, the 65 circle defined about the opening 9 being rela-

tively large so that the sound box is made to increase in size, after the manner for instance of an ordinary phonograph horn, away from the opening 15, and so that the sound box will entirely surround the opening 9 and thereby permit passage of sound waves outwardly through the post openings from all radial directions.

70 The saucer shaped, or cover, member 20 is provided with an opening 26 aligned with the opening 9 for free passage of the post, this opening being slightly larger than the diameter of the post so as to permit suitable passage of air for allowing movement of the weight past unapertured portions of the post.

75 The main body of the weight is usually made as a simple casting of lead or a suitable alloy thereof, the rib 22 being formed as an integral part of said casing.

80 The cover member 20 is usually made as a stamping of thin sheet metal and when in position it cooperates with the body G first, to constitute the upper wall of the sound box, second, to provide the opening 26 for cooperating with the post openings to determine 90 the sounds produced, third, to serve as a retaining ring for holding the bellows H connected with the body G, and fourth, as a neat finish and desirable weight addition to 95 said body G.

100 It will be understood that in operation the device constructed as described may be placed for instance in the body of a doll or other toy. Whenever the doll is moved from one position to another, as from a standing to a reclining position, the weight will slide along the post, for instance from bellows distending to bellows collapsing position. When the 105 doll is returned to standing position the weight will slide again to bellows distending position. Whenever the doll is moved to cause the weight to slide to bellows collapsing position the air from the bellows will be forced outwardly through the sound device 11, along the length of the sound box and through the 110 post openings 17 causing the sound device to produce a sound according to the varying volumes of air passing as determined by the size, disposition, etc. of the post openings.

115 The device as thus constructed is simple and practical to manufacture. It may be cheaply produced. The required length of the post for producing any desired kind of sound may be maintained at a minimum, and the operation will be thoroughly efficient and satisfactory.

120 As many changes could be made in this construction without departing from the scope of the invention as defined in the following claims, it is intended that all matter contained in the above description or shown in the accompanying drawings, shall be interpreted as illustrative and not in a limiting sense.

125 Having thus described my invention, what 130

I claim as new and desire to secure by Letters Patent is:—

1. A sound producing device comprising a casing, a sound producing element, a weighty member movable by gravity within the casing to produce a flow of air for operating the sound producing element, said weighty member on one side thereof having a shallow elongated sound receiving chamber the longer dimension of which is positioned parallel to the plane of said weighty member, said member having a passage for conducting sound from the sound producing element to said chamber, said chamber having a wall provided with a sound emission opening therein, and means for interrupting the emission of sound through said opening in the gravity movement of said weighty member.
2. A sound producing device comprising a casing, a weighty member movable by gravity in said casing for substantially the full length thereof, an elongated sound producing element mounted upon said weighty member and positioned in a plane parallel therewith, said weighty member in its gravity movement causing a flow of air for operating said sound producing element, said weighty member being provided with a shallow sound receiving chamber having its longer dimension extending in a plane parallel with the plane of said member and the sound producing element and said member provided with a passage affording communication between the sound producing element and said chamber, one wall of the sound receiving chamber having a sound emission opening therein, and means for interrupting the emission of sound through said opening in the gravity movement of said weighty member.
3. A sound producing device comprising a casing, a bellows within said casing having a tubular flexible wall, a fixed head connected

with the casing and closing one end of the bellows chamber, a gravity movable head secured to the other end of said tubular bellows wall, an elongated sounding reed mounted upon the inner side of said head and through which air is expelled from the bellows chamber in the movement of the head in one direction, said head at the opposite side thereof having a shallow elongated sound receiving chamber, the longer dimension of said chamber and the sound producing reed extending in parallel relation to the plane of said head, one wall of said chamber having a sound emission opening therein, and means for interrupting the emission of sound through said opening in the gravity movement of the bellows head.

4. A sound producing device comprising a post, a weight supported by and mounted upon the post freely slidable therealong, an elongated sound producing element carried by the weight extending longitudinally in a direction transverse to the length of the post, said weight comprising an elongated sound box associated with the sound producing element and extending also longitudinally in a direction transverse to the length of the post, the sound producing element and the sound box being arranged at opposite sides of the weight, the weight having an opening therethrough communicating between said sound producing element and said sound box, and means whereby sliding movement of the weight along the post will produce interrupted passage of air through said sound producing element, through said opening, and through said sound box to thereby produce interrupted sounding of the sound producing element.

In testimony whereof I affix my signature.

ALEXANDER KONOFF.
